UNITED STATES PATENT OFFICE.

SAMUEL OLDHAM AND JOHN J. PADBURY, OF PHILADELPHIA, PENNSYLVANIA, ASSIGNORS TO GEORGE OLDHAM AND SAMUEL OLDHAM, TRADING AS GEORGE OLDHAM & SON, OF FRANKFORD, PHILADELPHIA, PENNSYLVANIA.

PNEUMATIC HAMMER.

SPECIFICATION forming part of Letters Patent No. 722,614, dated March 10, 1903.

Application filed April 12, 1901. Serial No. 55,462. (No model.)

To all whom it may concern:

Be it known that we, SAMUEL OLDHAM and JOHN J. PADBURY, citizens of the United States, residing at Frankford, in the city of Philadelphia, in the county of Philadelphia and State of Pennsylvania, have jointly invented certain new and useful Improvements in Pneumatic Hammers, of which the following is a specification.

Our invention has relation to that class of pneumatic tools or hammers which are employed in the drilling, chipping, and dressing of stone or rock, as well as in riveting, calking, or hammering operations, and in such connection it relates to the construction and arrangement of such a tool or hammer.

The principal objects of our invention are, first, to provide in a pneumatic tool a reciprocating piston or hammer traversing the interior of a cylinder and a valve having a range of movement in the upper end of said cylinder, the valve and piston controlling the volume of live air or fluid entering the cylinder, so that upon the downstroke of the piston the piston moves with a gradually-accelerated movement as more and more live air is admitted; second, to provide in such a tool means whereby upon the upstroke of the

hammer or piston the travel of said hammer or piston is gradually checked; third, to provide in such a tool an arrangement of exhaust and live air ports and passages controlled by the valve and by the piston in such a manner that after the piston has been checked in its upper movement the valve is operated to reverse the movement of the piston, and, fourth, to provide in such a tool an arrangement of ports and passages for live air and exhaust air and a piston and valve controlling the same, so that the shock of the hammer upon the casing of the tool is obviated without impairing the force exerted by the hammer upon the tool.

The nature and scope of our invention will be more fully understood from the following description, taken in connection with the accompanying drawings, forming part hereof, in which—

Figure 1 is a longitudinal sectional view of a pneumatic tool or hammer embodying main features of our invention. Fig. 2 is an enlarged sectional view of the upper end of the tool or hammer and taken on the same plane as Fig. 1, but illustrating the other side of the interior of the tool. Fig. 3 is a cross-sectional view taken on the line 3 3 of Fig. 1. Fig. 4 is a longitudinal sectional view taken on the line 4 4 of Fig. 3 and looking toward the left of said Fig. 3, and Fig. 5 is horizontal sectional view taken on the line 5 5 of Fig. 3 and looking down upon the lower half of the tool.

In the drawings our invention is illustrated as applied to a tool of the type illustrated in the Letters Patent No. 590,661, granted September 28, 1897, to Frank E. Harthan, in which the hammer or piston travels or has a stroke longer than the length of said hammer or piston. Our tool also is provided with a grasping-handle provided with a valve controlling the admission of the air or fluid to the tool proper, such handle and valve being of a construction well known in the art.

Referring to the drawings, *a* represents the interior cylinder in which the hammer or piston *b* is adapted to travel, and *c* represents the outer casing or shell surrounding the cylinder *b* and also carrying the tool-holder *c'*, in which the shank *c*² of the tool *c'* is held in any well-known manner. With the tool supported in the position illustrated in Figs. 1 and 3 near the upper end of the cylinder *a* and in the top of its wall is formed a slot or opening *a'*, extending through the wall and in alignment with the port *d*, through which live air or fluid passes from the handle *d'* to the upper end of the cylinder *b*. This slot *a'* is therefore the main inlet-port for live air. Diametrically opposite to but slightly above the main inlet-port *a* another opening *e* is cut through the lower part of the wall of the cylinder and terminating in a longitudinal groove or channel *e'*, formed between the cylinder *a* and casing *c*. This channel *e'* terminates in an opening *e*², passing through the wall of the cylinder *a* at its extreme lower end. A valve *f*, to be hereinafter more fully described, controls the opening or port *e*, so

that it may on the upstroke of the hammer *b* communicate with the entrance or main inlet-port *a'* to permit live air to pass along the outside of the cylinder through the channel *e'* and to enter the cylinder through the opening *e²* below the lower face of the hammer *b* and so that on the downstroke of said hammer *b* the port or opening *e* may communicate with the main exhaust port or outlet *g*. The channel *e'*, by preference, is formed by cutting into the external periphery of the cylinder *a*, because that is the simplest and easiest way to construct the tool. For the same reason all the longitudinally-arranged channels hereinafter described are likewise preferably cut in the external surface of said cylinder *a*. The valve *f* is provided with an upper head *f'*, a lower head *f²*, and an intermediate head *f³*, so as to form between its ends *f'* and *f²* two openings or chambers *f⁴* and *f⁵*. The heads *f'* and *f²* fit closely in the main bore of the cylinder *a*. The upper head *f'* has a flange *f⁶*, which slides in an enlarged bore *a²*, forming a chamber at the upper end of the cylinder *a*. When the piston or hammer *b* is about to begin its upstroke, the valve *f* occupies the lowermost position in the cylinder *a*, so that its upper opening or chamber *f⁴* forms a connection between the main live air inlet *a* and the opening *e*, leading live air to the channel *e'* and port *e²* to the bottom of the cylinder *a* below the hammer *b*. When, however, the valve *f* is lifted, as illustrated in Fig. 4, the intermediate head *f³* of the valve closes the main live-air port *a'*. At substantially right angles to the ports *a'* and *e* and in the upper end of the wall of the cylinder *a* are cut three openings *h*, *h'*, and *h²*. The lower opening *h* of these openings is situated some distance below the lower head *f²* of the valve *f* and is not controlled by said valve. The intermediate opening *h'* is narrower than the openings *h* and *h²* and is adapted to be covered by the lower head *f²* of the valve *f* when said valve is in its lowermost position and to be uncovered and below said head *f²* when the valve *f* is in its uppermost position. The upper opening *h²* is always in alignment with the lower chamber *f⁵* of the valve *f*. The three openings *h*, *h'*, and *h²* are all connected by a longitudinal channel *h³*, as clearly illustrated in Figs. 2 and 5. Diametrically opposite the openings *h*, *h'*, and *h²* in the upper end of the wall of the cylinder *a* are cut two openings *k* and *k'*. The upper of these openings *k* is in alignment with the main exhaust port or outlet *g* of the tool. The lowermost opening *k'* communicates by the longitudinal channel *k²* with the opening *k*. The opening *k* is controlled in the movement of the valve *f* by the upper head *f'* of said valve and is either closed by said upper head *f'* or communicates with the upper chamber *f⁴* of said valve. The lower opening *k'* is controlled by the lower head *f²* of the valve *f* and is either in communication with the lower chamber *f⁵*

of the valve *f* or closed by the lower head *f²* of said valve. When the opening *k* is closed, the opening *k'* communicates with the chamber *f⁵* and when the opening *k'* is closed the other opening *k* communicates with the chamber *f⁴*. The function of these openings *h*, *h'*, and *h²* and of the openings *k* and *k'* will be hereinafter fully described. The exterior of the cylinder *a* is also provided with a longitudinal channel *m*, terminating at one end in the bore or chamber *a²* and at its lower end in an opening *m'* cut through the wall of the cylinder *a* at a point somewhat above the upper head of the hammer *b* when said hammer is in its lowermost position in striking engagement with the shank *c²* of the tool *c*. The opening *m'* and channel *m* for convenience may be called the "flip-opening" and the "flip-channel."

The operation of the tool is as follows: The hammer *b* having been forced down upon the shank *c²* of the tool *c* rebounds sufficiently so that it will cover the flip-opening *m'*. At this moment the valve *f* is in its lowermost position, as indicated in Figs. 1 and 2. The main inlet *a'* for live air communicates through the opening or chamber *f⁴* of the valve *f* with the opening *e*, channel *e'*, and port *e²*, and hence live air is forced to the lower end of the cylinder *a* below the lower head of the hammer *b*. The hammer travels upward in the cylinder *a* until it clears the flip-opening *m'*, when live air, partly diverted from the lower end of the cylinder *a*, enters the opening *m'* and the channel *m* and is discharged into the chamber *a²* above the flanged head of the valve *f* and serves to maintain the valve *f* in its lowermost position. The air above the upper head of the hammer *b* is forced by the travel of the hammer into the lower opening *h* and channel *h³*. In all positions of the valve *f* the upper opening *h²* of the channel *h³* is always in communication with the chamber *f⁵* of the valve *f*, and in the lowermost position of the valve *f* this chamber *f⁵* is in open communication through the exhaust-opening *k'* and channel *k²* with the main exhaust-port *g*. It follows, therefore, that for a portion of the travel upward of the hammer *b* the exhaust-air in the cylinder *a* is forced out through the opening *h* into the exhaust-port *g*. When, however, the hammer *b* reaches the position illustrated in Fig. 4, the port or opening *h* is closed by the upper head of the hammer *b*, and therefore the air above the hammer *b* is confined in the cylinder *a* between the upper head of the hammer *b* and the lower head *f²* of the valve *f* and will be compressed by the further advance of the hammer. This compression of the air serves to check or break the further upward movement of the hammer, and it also serves to force the valve *f* toward its uppermost position when the pressure on the lower head *f²* of said valve *f* is greater than the pressure of live air in the chamber *a²* upon the flanged head *f⁶* of said valve.

The valve f then moves until its intermediate head f^3 first cuts off entirely the port or main live-air inlet a' , and then brings said inlet a' into communication with the chamber f^5 of the valve f at the precise moment the hammer b completes its upward stroke. This position is illustrated in Fig. 5. In this position live air passes from the inlet a' through the chamber f^5 and through the upper opening h^2 into the channel h^3 . As before explained, the lower opening h is closed by the hammer b ; but the narrow intermediate opening h' is cleared by the lower head f^2 of the valve f . The live air thus passes through the narrow opening h' into the cylinder a above the upper head of the hammer b . The hammer is thus initially forced downward under the pressure of but a portion of the live air until the hammer clears the lower opening h , when the full force of the live air or fluid acts upon the hammer and accelerates its movement toward the shank of the tool c^3 . As the hammer travels downward the exhaust in the cylinder a is forced out through the port e^2 , channel e' , and port e into the upper chamber f^4 of the valve f , from whence it passes into the opening k and exhaust-outlet g . When the upper head of the hammer b in its downward travel passes the flip-opening m' , the live air, partly diverted from the cylinder a , passes through the opening m' and channel m into the chamber a^2 against the flanged head of the valve f and forces said valve downward, so that the air-inlet a' is first closed by the valve and then brought into communication with the chamber f^4 of the valve f , which position is indicated in Figs. 1 and 2. The operation then continues as above described. The impact of the hammer or piston upon the shank of the tool materially assists in the shifting of the valve to its lowermost position.

Having thus described the nature and objects of our invention, what we claim as new, and desire to secure by Letters Patent, is—

1. In a pneumatic tool or hammer, a cylinder, a piston or hammer adapted to reciprocate in a portion of said cylinder, a valve adapted to reciprocate in the remaining portion of said cylinder and means controlled by the movement of both piston and valve for admitting live air or fluid to the cylinder above the piston on its downstroke in varying volume, so that the downward movement of the piston is accelerated after it has begun to travel.

2. In a pneumatic tool or hammer, a cylinder, a piston adapted to reciprocate therein, a valve having a range of movement beyond the upstroke of the piston, partly in the upper end of the cylinder and partly in an enlarged chamber forming a continuation of

said cylinder, combined with means for directing the pressure of live fluid toward an upper enlarged head, formed on the valve, 65 moving in said chamber, and means for compressing the exhaust within the cylinder between the piston and a lower solid head formed on said valve, both means being controlled by the piston during its upstroke toward the valve. 70

3. In a pneumatic tool or hammer, a cylinder, a piston adapted to reciprocate in a portion of said cylinder, a valve adapted to reciprocate in the remaining portion of said cylinder and having a lower head or end closing the inner bore of said cylinder and means controlled by the piston and valve for first checking the upward movement of the piston by cushioning the air between said piston and lower head of said valve and then shifting the valve to reverse the movement of the piston. 75

4. In a pneumatic tool or hammer, a cylinder, a piston or hammer having a range of 85 movement therein, and a valve located within the cylinder above the hammer and in the path thereof, said valve and piston mutually co-operating to control each other and said valve having a lower head completely closing 90 the inner bore of said cylinder.

5. In a pneumatic tool or hammer, a cylinder, a piston or hammer having a range of movement therein, a valve traversing the upper end of the cylinder and having a lower 95 head closing the inner bore of the cylinder, said valve arranged in the path of the piston or hammer, and moving in the same direction as the piston or hammer in the reciprocation thereof, and said piston or hammer and valve 100 mutually co-operating to control each other.

6. In a tool or hammer of the character described, a cylinder, wherein the hammer or piston is adapted to reciprocate, a valve arranged in the cylinder and having a lower 105 head closing the inner bore of the cylinder at a point beyond the stroke of the piston or hammer, said valve having lower, upper and intermediate heads, and chambers or openings formed between the intermediate and end heads and said valves and its heads controlling the actuation of the piston or hammer, and said piston in conjunction with the heads and chambers controlling the operation 110 of said valve. 115

In testimony whereof we have hereunto set our signatures in the presence of two subscribing witnesses.
